UNITED STATES PATENT OFFICE.

JACOB P. HOLLENBECK, OF FREDERICK, OKLAHOMA.

OIL-GAS BURNER.

1,003,109.

Specification of Letters Patent. Patented Sept. 12, 1911.

Application filed January 4, 1911. Serial No. 600,806.

To all whom it may concern:

Be it known that I, JACOB P. HOLLENBECK, citizen of the United States, residing at Frederick, in the county of Tillman and 5 State of Oklahoma, have invented certain new and useful Improvements in Oil-Gas Burners, of which the following is a specification.

My invention relates to oil burners and 10 particularly to that type of oil burner in which steam is injected with the oil into a generating chamber for the purpose of securing a more perfect combustible gas.

The primary object of my invention is to 15 provide a very simple, effective, easily operated and easily cleaned oil burner of that type in which jets from the gas generating chamber are used to heat water in the reservoir and thereby create steam to be injected 20 into the generating chamber.

A still further object is to provide a construction in which the steam is superheated and then carried to the gas generating chamber to be mixed with the oil.

25 A still further object is to provide a construction in which the steam after it passes from the steam superheating chamber will act to more fully atomize the oil coming from the supply pipe and thus break up 30 the particles of oil, thus securing a more perfect gasification of the fuel and a more complete and uniform intermingling of the particles of steam with the particles of oil.

My invention is illustrated in the accompanying drawings, wherein:

Figure 1 is a perspective view of one form of my improved burner. Fig. 2 is a vertical transverse section thereof. Fig. 3 is a horizontal section on the line 3—3 of Fig. 2. 40 Fig. 4 is a view similar to Fig. 3 but showing a modified form of burner in which two steam superheating chambers are provided, and Fig. 5 is a transverse section of Fig. 4 on the line 5—5 thereof.

45 Corresponding and like parts are referred to in the following description and indicated in all the views of the accompanying drawings by the same reference characters.

Referring now more particularly to Figs. 50 1, 2 and 3, 2 designates the base, this base being hollow to provide a water reservoir and steam generator 3 which is connected by a supply pipe to any suitable source of supply. Supported above the base 2 and 55 in spaced relation thereto is a gas generating chamber composed of the trough 4 having

ing upwardly extending sides 5 and a cover 6 having downwardly extending sides fitting snugly within the sides 5. This cover-plate is preferably arched and preferably 60 is formed with a longitudinally extending crown 7 connected to the arched top of the cover by vertical walls. These vertical walls are provided with perforations 8. Perforations 9 are also formed in the arched portion of the sides of the cover, as illustrated in Fig. 2. These perforations are for the passage of gas and the gas is ignited at these perforations.

The gas generating chamber is supported 70 in spaced relation to the steam generator or base and for this purpose I have provided the base with the upwardly extending lugs 10 at opposite ends of the base and provided the bottom of the trough 4 with the downwardly extending pairs of ears 11 adapted to fit over the lugs 10. One end of the trough 4 preferably rests upon an upwardly extending flange 12 at one end of the base 2. The other end of the base is also provided 75 with an upwardly extending flange 13, but the gas generating chamber is less in length than the base, and hence an air passage is provided between the gas generating chamber and the flange 13 as illustrated 80 in Fig. 1. This provides for an inlet of air to the burners which heat the water in the reservoir or water chamber 3. Both sides of the upper plate of the base 2 are provided with the upwardly extending flanges 14 90 which are however, relatively low in comparison with the flanges 12 and 13, thus providing for the outlet of flames between the flanges 14 and the adjacent wall of the gas generating chamber for a purpose to 95 be later stated.

The trough 4 forming the bottom of the gas generating chamber is provided with a plurality of nipples 15. These nipples project up into the generating chamber and 100 also project down below the bottom of the trough 4 toward the upper plate of the base 2 as at 17. These nipples 15 are for the purpose of conducting the gas from the generating chamber and projecting the gas in 105 the form of burning jets against the top of the steam generator. The gas generating chamber is also provided with nipples 16 which also extend through and project below the under face of the bottom of the trough 4 110 and carry off and lower the level of the surplus oil, where the oil accidentally has

such depth within the chamber 4 as to cover the top of the nipples 16. In normal circumstances, however, whatever oil is within the chamber 4 will be below the level of the tops of the nipples 15 or 16.

Water is admitted to the steam generator 3 by means of a conducting pipe 18 provided with a regulating valve 19, while oil is admitted to the gas generating chamber by 10 means of an oil intake pipe 20 provided with a valve 21. This oil intake pipe is connected by a pipe 22 to the steam space of the reservoir 3. This pipe 22 preferably extends from a steam superheating chamber 23 15 which is connected to the steam space of the water reservoir.

Preferably, and as illustrated in Figs. 1 and 2 the superheating chamber 23 is formed as part of the base 2 and is provided with 20 openings 24 leading into the upper portion of the water reservoir 2 above the water line thereof. The chamber 23 is formed by coring out the material from which the base and the superheating chamber are made. 25 The pipe 22 extends from the upper portion of the superheating space 23 and extends preferably over the top of said superheating chamber and then downward and laterally where it joins the pipe 20. The superheated 30 steam passing through the pipe 22 is ejected into the pipe 20 and acts to spray the oil and steam into the generating chamber.

The operation of this form of my invention is obvious.

35 Oil is admitted through the pipe 20 until it covers the bottom of the gas generating chamber and overflows through the nipples 16 and 15 onto the top of the steam generator 3. The oil is then ignited and the flames 40 extending up on each side of the gas generating chamber tend to vaporize the oil in the chamber and create gas, at the same time of course, tending to heat the water in the chamber 3. As the gas is formed it issues 45 through the nipples 15 and is projected against the top of the water reservoir, heating the same and causing steam to be formed. This steam, in the construction illustrated in Figs. 1 and 2 passes into the superheater 50 23. The flames which pass upward from the upper face of the reservoir between the gas generating chamber and the superheater will reheat the steam in the superheater and this dry, heated steam passes by means of 55 the pipe 22 into the pipe 20, and as before stated, projects the mixed steam and oil into the gas generator chamber. The gas which is evolved in the generator is lighted at the openings 8 and 9. It is to be understood 60 that while I prefer to use the superheater, I do not wish to limit myself to this use. It will be seen that the pipe 22 is connected to the steam space of the steam generator by means of the superheater.

65 The particular form of my device which

is shown in Figs. 1, 2 and 3 is intended to be used for ordinary stoves. Where, however, a greater amount of heat is desired I increase the steam space and double the capacity of the superheater by adding another superheater on the opposite side of the burner from the first named superheater. Such a construction is illustrated in Figs. 4 and 5. In these figures 25 designates the steam generator and 26 the oppositely disposed superheating chambers which are formed integral with the water reservoir and extend upward on either side thereof. The upper plate 27 of the steam generator is formed to provide a fire-pan, as previously described, and is provided with the upwardly extending end-flanges 28 and the side flanges 29, corresponding to the flanges 12 and 14, respectively. It is also provided with the oppositely disposed lugs 30. The gas generator 85 is precisely the same as that previously described and comprises the body portion 31 provided on its under side with the oppositely disposed pairs of spaced lugs or ears 32 fitting over the lugs 30. A cover section 90 33 fits down into the trough shaped body portion as previously described, and is provided with a plurality of perforations. In this form of my invention I have shown three bands of these perforations 34. Like 95 the gas generating chamber previously described, the gas generating chamber in this form of my invention is likewise provided with a plurality of tubular nipples 35, whereby the jets of gas may be directed 100 against the steam generator. One or more of these nipples is less in height than the remaining nipples, so as to form means for conducting off surplus oil when the burner is primed. There are two superheating chambers 26 one on each side of the steam chamber 25 and having openings 36 connecting the two. The upper end of one superheater is connected by a pipe 37, to one end of the 105 gas generating chamber while the other superheater is connected by a pipe 38 to the other end of the gas generator through the pipe 39, which is provided with the valve 40. The dry steam passing into the pipe 39 forces the fuel into the gas generator in the 110 form of a finely divided spray. This spray of mingled gas, steam and oil is met by the spray of dry steam coming from the pipe 37 and this collision of particles tends to more fully mix the steam and oil and form a more uniform gas, thus giving a greater efficiency 115 to the burner. The base which forms the water reservoir and steam chamber and the superheating chamber are preferably cast in one piece and these parts are provided with openings whereby the interior of the water reservoir and the superheating chambers 120 may be cleaned out when desired.

I have found in practice that my invention is very effective, and is capable of giving 130

ing a great amount of heat in proportion to its size. The burner is very simply constructed, may be easily taken apart as there are no delicate parts to get out of order and it is capable of very easy cleaning. It may be applied to any ordinary stove, furnace or like heater.

Having thus described the invention what is claimed as new is:—

19 1. An oil burner including a sectional gas generating chamber having a vapor outlet opening in its upper portion, a steam generator located below and coextensive with the gas generating chamber and spaced therefrom, a fuel supply pipe communicating with the generating chamber, burners located in the bottom of the generating chamber and directed toward the steam generator, and means for conducting the steam from the steam generator to the gas generating chamber.

2. An oil burner including a gas generating chamber having a fuel inlet and vapor outlets and also having an overflow outlet, a steam generating chamber located beneath the gas generating chamber, the upper face of the steam generating chamber forming a pan to receive the overflow from the gas generating chamber, means for conducting steam from the steam generating chamber to the gas generating chamber, and means for discharging a flame against the steam generating chamber.

3. An oil burner including a hollow base forming a steam generating chamber, the upper face of the base forming an overflow collecting pan, a gas generating chamber mounted upon the base in spaced relation thereto and having burner nozzles directed toward said pan, a fuel supply pipe entering the gas generating chamber, and means for conducting steam from the steam generating chamber into the fuel supply pipe.

4. An oil burner including a base forming a steam generating chamber, a gas generating chamber located above the steam generating chamber and spaced from the same, burner nozzles extending from the gas generating chamber toward the steam generating chamber, a fuel pipe communicating with the gas generating chamber, and means for conducting steam from the steam generating chamber to the gas generating chamber.

5. An oil burner including a base forming a steam generating chamber, a gas generating chamber located above and spaced from the steam generating chamber, burner nozzles extending from the gas generating chamber toward the top of the steam generating chamber, a fuel pipe extending into the gas generating chamber, means for conducting steam from the steam generating chamber into the fuel pipe, and means whereby the liquid fuel used for priming the gas gen-

erating chamber may be conducted to the upper surface of the steam generating chamber.

6. An oil burner including a base forming a steam generator and having flanges upon its upper face defining a burning pan, a superposed gas generating chamber mounted upon the base and spaced from its upper face, said generating chamber being provided with openings at its top, a plurality of burner nozzles extending down from the gas generating chamber and directed toward the base, means for conducting fuel to the gas generating chamber, and means for conducting steam to said chamber from the steam generator.

7. An oil burner including a hollow base forming a steam generating chamber, flanges upon the upper face of the base and defining a fire-pan, a gas generating chamber mounted upon the base and spaced from the same, tubular nipples extending upwardly into the gas generating chamber from the bottom thereof, a fuel pipe entering the gas generating chamber, and means for conducting the steam from the steam generator to the fuel pipe.

8. An oil burner including a steam generator, a gas generator mounted above the steam generator and spaced therefrom, a superheating chamber connected to the steam space of the steam generator and extending up at one side of the gas generator and spaced therefrom, means for conducting liquid fuel to the gas generator, and means for conducting steam from the superheater to the gas generator.

9. An oil burner including a hollow base forming a steam generator, a steam superheating chamber connected to the steam space of said base and extending up above the base, a gas generating chamber mounted upon the base and having burner nozzles directed toward the base, said gas generating chamber being spaced from the superheating chamber, a pipe for conducting liquid fuel into the gas generating chamber, and means for conducting the steam from the superheating chamber to said pipe.

10. An oil burner including a hollow base forming a steam generator, a superheating chamber connected to the steam space of the base and extending upward at one side of the base, a gas generating chamber supported and spaced from the base and formed with burner nozzles directed toward the base, said generating chamber being spaced from the superheating chamber to permit the passage of heat between the two, a fuel inlet pipe extending into the generating chamber, and a steam pipe extending from the superheating chamber to the fuel inlet pipe.

11. An oil burner including a hollow base forming a steam generator, a superheating chamber formed integral with the base ex-

tending up at one side thereof, upwardly extending flanges on the top of the base forming a fire-pan, a gas generating chamber narrower than the base and supported thereon in spaced relation thereto, said generating chamber being also spaced from the superheating chamber, burner nozzles extending from the gas generating chamber toward the base, a fuel pipe entering the gas generating chamber, and a steam pipe extending from the upper end of the superheating chamber to said fuel pipe.

12. An oil burner of the character described including a hollow base forming a steam generating chamber the upper face of the hollow base being formed with upwardly extending supporting members, a steam

superheating chamber connected to the steam space of the steam generating chamber and extending up at one side thereof, a 20 gas generating chamber detachably supported upon the base and spaced therefrom and from the superheating chamber, burner nozzles extending from the gas generating chamber toward the base, a fuel pipe entering the gas generating chamber, and a steam pipe extending from the superheater into said fuel pipe.

25 In testimony whereof, I affix my signature in presence of two witnesses.

JACOB P. HOLLENBECK. [L. S.]
